UNITED STATES PATENT OFFICE

95,837

DESIGN FOR AN ENSEMBLE DRESS

Jack Kirschner, New York, N. Y.

Application April 8, 1935, Serial No 56,275

Term of patent 3½ years

To all whom it may concern:

Be it known that I, Jack Kirschner, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The diagonal and the cross hatching lines on the collar represent contrastingly colored bands which are edged with feather stitchings of contrastingly colored threads.

The diagonal and cross hatching lines on the belt represent contrasting colors, without stitchings.

I claim:

The ornamental design for an ensemble dress, substantially as shown and described.

JACK KIRSCHNER.
